UNITED STATES PATENT OFFICE.

ARTHUR MIDDLETON ROSE, OF YONKERS, NEW YORK, ASSIGNOR TO THE
W. & J. SLOANE, OF NEW YORK.

DESIGN FOR CARPETING.

SPECIFICATION forming part of Design No. 30,453, dated March 28, 1899.

Application filed January 6, 1899. Serial No. 701,404. Term of patent 3½ years.

To all whom it may concern:

Be it known that I, ARTHUR MIDDLETON ROSE, a citizen of the United States, and a resident of Yonkers, in the county of Westchester and State of New York, have invented a certain new and original Design for Carpeting, of which the following is a specification.

My design, as shown in the drawing, consists in a new design for carpeting.

10 The design is characterized by loosely-constructed bouquets of flowers and foliage intended to represent roses and rose-foliage combined with trusses of lilac or hardy hydrangea. These bouquets gain importance 15 from being sparsely disposed upon a background which consists of wreath-like figures of conventional flowers, adjacent wreaths be-

ing connected by spray-like ornaments. To show the bouquet-figure of the drawing more perfectly, a portion of the background of spray-connected wreaths is omitted in the drawing.

What I claim as new, and desire to secure by Letters Patent, is—

The design for carpeting, substantially as shown and described.

In testimony whereof I have signed my name to this specification in the presence of two subscribing witnesses.

ARTHUR MIDDLETON ROSE.
